UNITED STATES PATENT OFFICE

152,537

DESIGN FOR A PORTABLE PICTURE SCREEN

John T. Heck, Elmhurst, and Leo J. Du Mais and
Curtis O. Talbot, Chicago, Ill., assignors to Da-
Lite Screen Company, Inc., Chicago, Ill., a cor-
poration of Illinois

Application July 3, 1947, Serial No. 140,093

Term of patent 14 years

(Cl. D61—1)

To all whom it may concern:

Be it known that we, John T. Heck, residing at Elmhurst, in the county of Du Page and State of Illinois, Leo J. Du Mais, residing at Chicago, in the county of Cook and State of Illinois, and Curtis O. Talbot, residing at Chicago, in the county of Cook and State of Illinois, all citizens of the United States of America, have invented a new, original, and ornamental Design for Portable Picture Screen, of which the following is a specification, reference being had to the accompanying drawing, forming part thereof.

Figure 1 is a perspective view of a portable picture screen in partially folded condition, showing our new design.

Figure 2 is a side elevational view thereof.

Figure 3 is a bottom plan view thereof.

We claim:
The ornamental design for a portable picture screen, as shown.

JOHN T. HECK.
LEO J. DU MAIS.
CURTIS O. TALBOT.
